UNITED STATES PATENT OFFICE

165,081

COMBINED CAPE AND SCARF

Tina Leser, New York, N. Y.

Application March 21, 1951, Serial No. 14,570

Term of patent 3½ years

(Cl. D3—3)

To all whom it may concern:

Be it known that I, Tina Leser, a citizen of the United States, residing in New York city, in the county of New York and State of New York, have invented a new, original, and ornamental Design for a Combined Cape and Scarf, of which the following is a specification, reference being had to the accompanying drawing, forming part thereof.

Fig. 1 is a front view of a combined cape and scarf showing my new design, and

Fig. 2 is the rear view thereof.

I claim:

The ornamental design for a combined cape and scarf, substantially as shown.

TINA LESER.
